(57) **CLAIM**

The ornamental design for a charging station as shown and described.

DESCRIPTION

FIG. 1 is top front right perspective view of a charging station showing my new design;
FIG. 2 is right side view thereof;
FIG. 3 is a left side view thereof;
FIG. 4 is a rear view thereof;
FIG. 5 is a front view thereof;
FIG. 6 is a top view thereof; and,
FIG. 7 is a bottom view thereof.

The evenly-spaced broken lines in the Figures illustrate portions of the charging station that form no part of the claimed design.
